DESIGN FOR AN ADJUSTABLE LAMP

Max E. Kraft, Cleveland, Ohio, assignor to Cuyahoga Furniture and Lamp Company

Application April 18, 1939, Serial No. 84,359

Term of patent 7 years

To all whom it may concern:

Be it known that I, Max E. Kraft, a citizen of Latvia, residing in the city of Cleveland, county of Cuyahoga and State of Ohio, have invented a new, original, and ornamental Design for an Adjustable Lamp, of which the following is a specification, reference being had to the accompanying drawing, forming a part thereof.

shown in Figure 1 with the bracket in closed position; and

The dominant feature of the design resides in the portion shown in solid lines.

I claim:

The ornamental design for an adjustable lamp, substantially as shown and described.

MAX E. KRAFT.
